DESIGN FOR A COMBINED DISPLAY RACK, OIL SAVER, AND WASTE CAN RECEP- TACLE

Harvey J. Smith, Danville, Va., assignor of one-
third to W. Ira Barker, Danville, Va., and one-
third to Ed E. Mayo, Orlando, Fla.

Application August 17, 1945, Serial No. 121,451

Term of patent 7 years

(Cl. D80—9)

To all whom it may concern:

Be it known that I, Harvey J. Smith, a citizen of the United States of America, residing at Danville, in the county of Pittsylvania and State of Virginia, have invented a new, original, and ornamental Design for a Combined Display Rack, Oil Saver, and Waste Can Receptacle, of which the following is a specification, reference being had to the accompanying drawing, forming part thereof.

Fig. 1 is a perspective view of a combined display rack, oil saver and waste can receptacle, looking at the open side and front of the same and showing my new design.

Fig. 2 is a rear elevational view of the same.

Fig. 3 is a side elevational view of the same, looking at the open side.

Fig. 4 is a side elevational view of the same, looking at the closed side (the side opposite that shown in Fig. 3).

Fig. 5 is a top plan view of the same.

I claim:

The ornamental design for a combined display rack, oil saver and waste can receptacle, substantially as shown.

HARVEY J. SMITH.
